INTERNAL COMBUSTION ENGINE

John Harlin Geisse, Washington, D. C.

Application July 24, 1937, Serial No. 155,533

4 Claims. (Cl. 74—50)

My invention relates to displacement pumps and power units and has for its object the simplification of such units.

I attain this objective by employing a novel combination of transmission mechanism, cylinders, and pistons in which the cylinders are arranged in the form of a polygon and a single, solid transmission member converts the simple harmonic motion of the pistons to the rotary motion of the crank shaft.

One form of construction as applied to an internal combustion engine is illustrated in the accompanying drawings, in which:

Figure I is a section in the plane of the center lines of three cylinders; Figure II is a typical section through a cylinder at its exhaust ports; Figure III is a typical section through a cylinder at its intake ports; Figure IV is an end view with the cover plate removed showing the crank mechanism; Figure V is a vertical section through the complete engine; Figure VI is the cover plate; and Figures VII and VIII are sections similar to Figures IV and V but showing an alternate mechanism.

Similar numerals refer to the same or identical parts throughout the several views.

The casting 1 incorporates the cylinders and crankcase. The center lines of the cylinder bores 2 form an equilateral triangle. The combustion chambers 3 located at the corners of the triangle communicate with the two cylinder bores 2 whose center lines form the adjacent legs of the triangle. Each cylinder is provided with both inlet and exhaust ports 6, the exhaust ports serving the combustion chamber at one end of the cylinder and the intake ports serving the combustion chamber at the opposite end of the cylinder. The ports 6 are controlled by the double ended pistons 4. Exhaust manifolds 7 have exhaust outlets 9. Inlet manifolds 5 circling the cylinders communicate with an inlet manifold 8 running adjacent and parallel to the cylinders.

Each double faced piston 4 is provided with a square piston pin 10 which extends through the wall of the cylinder and into cross-head slots 12. The piston pin extension outside of the piston is further extended perpendicular to the cylinder center line to make sliding contact with flat surface 21 in the cylindrical crankcase section of casting 1.

Shaft 14 is provided with an eccentric 13 which operates in the cylindrical element 11. Actuated by the eccentric 13 and the piston pins 10, element 11 is constrained to move in a circle but restrained from rotation around its own axis.

Element 11 is provided with ports 15 which register at the proper time with ports 17 in the cover plate 20. Ports 17 communicate with inlet manifold 19 provided with an opening 18 to which a carburetor may be attached.

Openings 16 in the crankcase section communicate with the inlet manifolds 8.

In Figures VII and VIII, 25 is the wrist pin which is provided with a flat dish end 22. 23 is a pin fastened in element 11 and passing through 10 the dish extension 22 of the wrist pin 25. The wrist pin is free to slide in and out of the piston. 24 is the usual type of vane for a vane pump.

The operation of the engine is as follows:

Element 11 moving in the cylindrical crankcase section of casting 1, in conjunction with the extensions of the piston pins 10, operates as the rotor of a vane type pump with three pumping chambers. Each chamber on its suction stroke draws in a charge through ports 15. On its exhaust stroke it pumps the charge through ports 16 and manifold 8 to the inlet port of the cylinder next succeeding the chamber in the direction of crank rotation. This piston in this cylinder opens and closes its ports in correct relationship with the discharge stroke of the pump chambers.

On entering the cylinder the charge is compressed between the pistons, reaching its minimum volume when the leading piston has passed 30° beyond its top position and the lagging piston 30 30° short of its top position. Fuel is injected or a spark plug fired at the proper time, depending on whether the operation is on the auto-ignition or spark-ignition cycle. The gas pressures are then transmitted through the mediums of the pistons 35 and piston pins to element 11 which in turn causes the shaft to rotate. The exhaust piston then uncovers the exhaust ports and the burned charge is expelled. While the exhaust ports are still open the inlet ports are opened and the scavenging completed. The inlet ports remain open after the exhaust ports close to permit the cylinder to 40 be supercharged. The cycle then repeats for this cylinder. The cycles of the other combustion chambers follow and lead by 120°.

In the operation of the mechanism shown in Figs. VII and VIII the functions of the cross-heads in the other views are performed by the rotation of the pistons, rotation of the piston pin 25 around pin 23 and a slight reciprocating motion of the piston pin in the piston. In this version it is necessary to provide the customary type of vanes to operate with element 11 for pumping purposes.

It will be obvious to one skilled in the art that

numerous deviations from the mechanisms described can be made without departing from the general principle herein disclosed. In the mechanisms described the piston pins are depended upon to prevent rotation of element 11 about its own axis. It might be preferable to prevent this rotation by providing more than one eccentric. A gear reduction can be readily incorporated by fixing a spur gear to element 11 and providing an internal gear on the power shaft to mesh therewith.

It will also be apparent to one skilled in the art that the three cylinders shown herein could be combined in one torus with the same results.

15 I am aware that prior to my invention two pistons operating in conjunction with one combustion chamber have been used. I am also aware that four cylinders have been arranged in rectangular form with combustion chambers at the corners. However, I am not aware of any attempt to arrange the cylinders as shown herein and it is only by such arrangement that the pistons may all be satisfactorily operated directly from one crank.

Therefore, I claim:

1. In combination, cylinders arranged in the form of a polygon, pistons operable in said cylinders, a crankshaft, and a single functionally solid transmission member interconnecting the pistons and crankshaft. 5

2. In combination a plurality of cylinders arranged in the form of a polygon, pistons operable in said cylinders, a crankshaft, and a functionally single crosshead element interconnecting the pistons and crankshaft. 10

3. In combination, three cylinders whose axes lie in the sides of an equilateral triangle, three double acting pistons operable therein, and a functionally single crosshead interposed between 15 the pistons and one or more crankshafts operating in unison.

4. In combination, three cylinders whose axes intersect in one plane, three double acting and interacting pistons operable therein, and a functionally single crosshead element interposed between the pistons and one or more crankshafts 20 operating in unison.

JOHN HARLIN GEISSE.
